UNITED STATES PATENT OFFICE.

JOHN NASH, OF NORTH YAKIMA, WASHINGTON.

TURBINE.

1,139,562.

Specification of Letters Patent. Patented May 18, 1915.

Application filed September 26, 1914. Serial No. 863,681.

To all whom it may concern:

Be it known that I, JOHN NASH, a citizen of the United States, residing at North Yakima, in the county of Yakima and State 5 of Washington, have invented a new and useful Turbine, of which the following is a specification.

The present invention relates to improvements in turbines, and more particularly to 10 that type of turbine in which an elastic pressure fluid such as steam is employed as the motive power, one object of the invention, being the provision of a turbine, in which the rotor is composed of a plurality 15 of disks disposed in spaced relation to provide steam passages therebetween and at the same time offer steam impact surfaces at various equi-distant points around the circumference of the rotor, so that the full 20 impact force and the maximum amount of the expansive force of the pressure fluid may be utilized.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the drawings Figure 1 is a longitudinal sectional view through the complete turbine. 35 Fig. 2 is a cross section taken approximately on lines 2-2 of Fig. 1. Fig. 3 is an enlarged detail sectional view showing the construction of the pressure fluid nozzle at its junction with the stator. Figs. 4, 5 and 6 are 40 sections and partial elevations of the other sections of the side of the rotor as illustrated in Fig. 2. Fig. 7 is an enlarged detail sectional view of one section of the rotor showing the various steam passages and the 45 vane for conducting the steam therethrough from the inlet or impact portion of its respective member to the exhaust. Fig. 8 is an enlarged detail perspective view of a portion of the vane carrying member. Fig. 50 9 is a view similar of a portion of the rotor shown in Fig. 2 showing a modified form of vane carrying member.

Referring to the drawings, the numeral 1 55 designates the two supporting members below the stator, which is composed of the lower section 2 and the upper section 3, said sections being constructed so as to provide

the rotor chamber 4 and the two exhaust chambers 5 and 5'. The partitions 6 and 6' which are carried by the two sections of 60 the stator also provide the exhaust ports 7 and 7' so that the rotor chamber is in communication with the chambers 5 and 5' at the opposite ends thereof and as near the center of the rotor chamber as is possible, 65 the exhaust ports 7 and 7' being substantially concentric of the rotor chamber.

Attached to the exterior of the stator are the nozzle casings 8, in the present instance four being shown, such casings each having 70 a steam inlet pipe formed centrally thereof for projecting the pressure fluid into the elongated nozzle portions 9 formed in the walls of the stator. The nozzle portions 9 are tapered inwardly and enter the chamber 75 4 at a tangent thereto so as to properly act upon to rotate the rotor R. Leading from each one of the respective exhaust chambers 5 and 5' are the exhaust pipes 11 and 11'.

The rotor R is composed of the central 80 plate 12 and the two end plates 13 and 13', the central plate 12 being an imperforate plate, while the plates 13 and 13' are provided with steam outlet ports (not shown) 85 which correspond with the outlet ports 21 of the sections of the rotor. Each section 14 is composed of approximately two plates 19 and a spacing spider or disk 12, so that a space is provided between the plates 19. After steam has abutted the edge a of the 90 plates 19, it finally follows the direction of the arrows (Fig. 1) through the passages caused by the transverse blades 22 to the exhaust ports 21 centrally of the rotor.

As shown clearly in Figs. 7 and 8, the 95 annular plates 19 are each constructed with a plurality of vanes 22 and 22', mounted in opposite directions so as to provide the transverse openings or ports 22'' and 22''' so that when the parts are assembled as 100 shown in Fig. 7, with a plate or annular member 19 between the respective disks 12', that two steam passages will be provided upon each side thereof, as clearly shown at 22^a and 22^b. Thus when the steam abuts the 105 edges a of the annular members 19, the same will first enter the passage at the left of the plate 19 as viewed in Fig. 7, or the passage 22^a where it will impinge the vane 22 and be directed to the slot 22'', thereby entering 110 the passage 22^b between the plates 19 and 12, and being again switched into the passage 22^a by the vane 22' through the slot 22'''. This action follows throughout the series

of vanes and until the steam is directed into the exhaust port 21. As shown in Figs. 2, 4, 5 and 6, these ports 21 are constructed differently for the four sets of vane carrying members of the present rotor. The vane carrying member nearest the center is constructed as illustrated in Fig. 6 with one port 21. The vane carrying member nearest the exhaust port 7 (Fig. 2) has four ports 21, while the one adjacent thereto (Fig. 4) has three ports 21, and the next vane carrying member (Fig. 5) has two ports 21. By this arrangement the innermost port is permitted an exhaust through the various vane carrying members to finally exit through the port 7 to the final outlet or exhaust pipes 11.

As illustrated in Fig. 9, the annulus 19' is constructed with a series of vanes 25 and 25', and as clearly illustrated are disposed in a series of three, those indicated at 25 being bent in an opposite direction to those indicated at 25', thus giving a greater impact space between the respective annular members 19' than where they extend transversely in a single vane, as illustrated in Fig. 8.

The rotor shaft 16 is provided with a longitudinal groove 16' for the reception of the key 17 and the locking screw 18 by means of which the rotor is properly clamped thereupon.

From the foregoing description, it is evident that when the steam is admitted through the respective pipes 10 that the same will be directed against the periphery of the rotor R, and as the various sections thereof are so arranged that four are disposed upon each side of the partition disk 12 with their impact edges *a* arranged quartering, as illustrated in Figs. 2, 4, 5 and 6, that a continuous rotative movement will be imparted to the rotor R, the pressure fluid being properly conducted between the passages 22^a and 22^b so as to finally be exhausted through the ports 21 at the opposite ends of the stator, the vanes as illustrated receiving the impact and expansive force of the steam so as to absorb all the possible power therefrom, from the initial impact to the final action of the expanded steam through the ports 21.

Each disk 13—13' is provided with a concentric spring pressed packing ring to abut the adjacent face of the end wall of the stator.

What is claimed is:

1. A turbine, including a stator provided with a cylindrical rotor chamber and two exhaust chambers, one at each end of and in communication with the rotor chamber, said rotor chamber being provided with a plurality of inlet ports disposed the full length thereof and tangentially thereto, and a ro-

tor having a central partition and two active members one at each side thereof, said partition dividing the pressure fluid to cause it to exhaust equally in each exhaust chamber. 65

2. A turbine, including a stator provided with a cylindrical rotor chamber and two exhaust chambers, one at each end of and in communication with the rotor chamber, said rotor chamber being provided with a plurality of inlet ports disposed the full length thereof and tangentially thereto, a rotor mounted in the chamber and composed of a centrally disposed partition disk, a segmental member at each side of the disk, said member being divided into a plurality of active pressure receiving spaces, and having means for guiding the exhaust 80 toward the center of the rotor, the rotor being hollow at the center and being in communication at its ends with the respective exhaust chambers. 75

3. A turbine, including a stator provided with a cylindrical rotor chamber and two exhaust chambers, one at each end of and in communication with the rotor chamber, said rotor chamber being provided with a plurality of inlet ports disposed the full 90 length thereof and tangentially thereto, and a rotor composed of a central partition disk, and two active members one upon each side of the disk each of said members being composed of a plurality of circular sections, 95 and each section having an impact surface and provided with a pressure fluid passage leading therefrom to the center of the rotor, said rotor at each side of the partition disk being provided with a pressure fluid 100 directing port in communication with the respective exhaust chambers.

4. A turbine, including a stator provided with a cylindrical rotor chamber and two exhaust chambers, one at each end of and in 105 communication with the rotor chamber, said rotor chamber being provided with a plurality of inlet ports disposed the full length thereof and tangentially thereto, a rotor having a central partition and two active 110 members one at each side thereof, said partition dividing the pressure fluid to cause it to exhaust equally in each exhaust chamber, each active member, including a plurality of disks and interposed vane carrying annuli, 115 the vanes of which are alternating so as to produce and to cause the steam to follow a zig-zag course from its point of impact to the point of exhaust.

In testimony that I claim the foregoing as 120 my own, I have hereto affixed my signature in the presence of two witnesses.

JOHN NASH.
